UNITED STATES PATENT OFFICE.

JOSEPH LEE SWEENEY, OF INDIANAPOLIS, INDIANA.

TYPEWRITING MACHINE.

Application filed June 18, 1923. Serial No. 646,079.

To all whom it may concern:

Be it known that I, JOSEPH LEE SWEENEY, a citizen of the United States, and resident of Indianapolis, in the county 5 of Marion and State of Indiana, have invented certain new and useful Improvements in Typewriting Machines; and I do hereby declare the following to be a full, clear, and exact description of the invention, such as will enable others skilled in the art to which it appertains to make and use the same.

This invention relates to improvements in typewriting machines and the like and 15 more particularly to an improved key-cap construction.

The object of my present invention is to provide a key-button cap which shall be made in a single piece of transparent material 20 suitably colored as to be restful to the eyes of the operator; which shall be applicable interchangeably to any key-button of the machine; which shall be easy of touch; which shall, with the addition of a 25 soft gasket, provide a yielding and pneumatic cushion, and which shall have no character in any manner produced thereon or made a part thereof.

With this and other objects in view, the 30 invention consists in certain novel features of construction as hereinafter set forth and pointed out in the claims.

In the accompanying drawings,—

Figure 1 is a view illustrating the manner 35 of application of my improvements to a key-button.

Figure 2 is a plan view.

Figure 3 is a sectional view with the cap on a key-button.

40 Figure 4 is a bottom plan view of the cap, and

Figure 5 is a horizontal sectional view of the same.

45 A portion of a key lever is shown at 1 and this is provided with a key-button 2 which includes in its construction a disk or member 3 having indicated thereon a letter or character and a transparent plate 4 covering said disk or member 3 and held in place by the inwardly-turned flange 5 of the key-button.

The key-button above described is that commonly employed with typewriting machines and receives my improved cap 6 in such manner as not to add materially to 55 the height of the key-button.

The cap 6 is made in a single piece of transparent material,—such as celluloid for example,—and it may be suitably colored so as to be restful to the eyes of the operator. The flanged or cylindrical portion of the cap surrounds the key-button and is depressed at one point so as to form an inward projection 7 to engage the peripheral portion of the key-button and thus hold the 60 cap in place. That portion of the cap which is disposed over the key-button is depressed or made concave as at 8 to better accommodate the finger of the operator. Located between the under face of the cap 70 and the flanged portion 5 of the key-button, is a gasket 9 preferably of soft rubber.

With my improvements the letter or character on the key-button may be readily seen through the transparent top of the cap and 75 thus the placing of a character on the cap is obviated and the wearing or blurring of the character will be prevented as the finger of the operator cannot come in contact therewith and the glass cover 4 for the character disk 3 will be kept clean. The gasket 9 so separates the cap from the upper face of the key-button that an air chamber 10 will be formed to cushion the touch and such cushioning is further enhanced by the 80 resilience of the soft rubber of which the gasket is composed.

Having fully described my invention what I claim as new and desire to secure by Letters-Patent, is:

1. A transparent key-button cap formed to embrace and cover a key-button, the face portion of said cap being depressed and clear to permit of observance therethrough of the character on the key-button, and an 90 annular gasket of soft material located within the cap between the flange and the depression thereof in position to engage the edge portion of the key-button.

2. The combination with a key-button 100 provided with a character designation and having a flanged portion at its edge, of a

cap of transparent material disposed over the character designation on the key having a depressed top and having a cylindrical portion embracing the key-button, and
5 an annular soft gasket held between the cap and the upper edge of the flange of the key-button at the cylindrical portion of the cap around the depressed top thereof.

In testimony whereof I have signed this specification in the presence of two sub-¹⁰scribing witnesses.

JOSEPH LEE SWEENEY.
